CLAIM

I claim the ornamental design for a tortilla turning utensil, as shown and described.

DESCRIPTION

FIG. 1 is a perspective view of a tortilla turning utensil, showing my new design in-use;

FIG. 2 is a perspective view thereof, illustrated with a tortilla omitted for clarity of illustration;

FIG. 3 is a left-side elevational view thereof;

FIG. 4 is a right-side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken lines showing a person's hands and a tortilla in FIG. 1 and an unclaimed portion of the handle in all of the figures depict environmental matter and form no part of the claimed design.
